MULTIPLE EFFECT GAS COMPRESSING APPARATUS

Application filed December 4, 1922. Serial No. 604,917.

My invention relates to multiple effect gas compressing apparatus, particularly to compressors for refrigerating systems, particularly to volatile liquid refrigerating systems. Its objects are to make new uses of and to simplify multiple effect compressors and to more easily change ordinary compressors to multiple effect compressors by the insertion of an improved multiple effect compressor device in the suction pipe of an ordinary compressor.

The nature of the invention enables an ordinary compressor of a given displacement, by being made multiple effect, to have greater capacity or economy or both. This is accomplished by enabling the compressor to take into its cylinder, gas or vapor and liquid at two or more different suction pressures, seriatim, in the increasing order of said pressures, so that a higher pressure fluid compresses a lower pressure fluid by mixing with it.

In the drawings:—Fig. 1 is a diagrammatic part sectional view of a compression system. Fig. 2 is a diagrammatic part sectional view of the high pressure suction piston actuated valve and its liquid pressure operating means.

Fig. 3 is a diagrammatic part sectional view of the high pressure suction piston actuated valve and its gas pressure operating means.

Fig. 4 is a diagrammatic part sectional view of a special form of a multiple effect compressor device.

Fig. 5 is a diagrammatic part sectional view of a special form of a multiple effect compressor device.

Figs. 6 and 7 are each diagrammatic views of a cam and its roller, used to directly or indirectly operate the high suction piston valve of a multiple effect compressor device.

Fig. 8 is a part sectional view of a practical form of a multiple effect compressor device in detail.

Figs. 9 and 10 are part sectional views of a practical form of pressure actuating means for one or more multiple effect compressor devices, Fig. 9 being more particularly for a hydraulic type and Fig. 10 being more particularly for a pneumatic type of pressure

actuating means, as later more specifically described.

Fig. 11 shows a multiple effect compressor device at each end of a double acting cylinder and Figs. 12 and 12a show a multiple effect compressor device on each of two single acting cylinders.

Figs. 13 and 14 are diagrammatic part sectional views of a four pressure multiple effect compressor device, Fig. 13 being a section on line 13, 13 of Fig. 14 and Fig. 14 being a section on line 14, 14 of Fig. 13.

Fig. 15 is a diagrammatic elevation of a multiple effect compression system.

In all the figures similar parts usually have like letters or numbers, sometimes with different subscripts.

In Fig. 1, ordinary double acting compressor cylinder A has its piston *h* reciprocated by its rod *g* by means of cross head *f*, connecting rod *e*, crank pin 14a, crank 14 and main shaft 15.

D and D₁ are multiple effect compressor devices each having low pressure suction inlets 5 leading from a low pressure refrigerator E (shown for D₁, but not for D) and high suction inlets 6 leading from a high pressure refrigerator F or from some other source of high pressure gas as from ordinary compressor A₁, shown for D₁ but not for D. Outlets 7 lead to compressor's suction valves *i*. Under certain conditions, described later, E is a high pressure and F a low pressure refrigerator. The compressor A has discharge valves *j* and discharge outlets *k* which lead via a pipe to condenser C. A liquid pipe leads from the condenser to expansion valves for the low and high pressure refrigerators, as will be clear to those skilled in the art without more detailed description. In operation gas enters 5 and passes valves 1 and *i* during any desired portion of the piston's low suction stroke, usually just before or at its end, then high pressure suction valve 2 in multiple effect compressor device D₁ is opened by means of cam 3, roller 4, shaft 9 in bearings 10, gears 19, and crank arm 12, engaging pin 13 in crank pin 14a, or in multiple effect compressor device D by pressure on piston 8 via pipe 17 leading from outlet 16a, *b*, (see also 10

Fig. 15), of actuating means 16 actuated by shaft 9. When valve 2 is so opened it allows high suction pressure gas to flow via inlets 6 and compressor valves *i* into compressor cylinder to join with and compress the low pressure gas therein and so make room for itself and when the cam 3 and roller 4 of D_1 or the piston 8 of D cease to lift valve 2, it is reseated by any desired means *s*, such for example, as a spring.

Heretofore I have used mechanical means to actuate valve 2, as in multiple effect compressor device D_1 . I found that this usually required about one lever arm, 10 gears, 12 bearings and three couplings for each pair of multiple effect compressor devices, whether for a single acting or double acting compressor. I have found that this considerable quantity of operating mechanism required special supports and I found it very difficult to clear the many pipes and other existing parts of an ordinary compressor and I found that a specially designed layout was required and that the multiple effect compressor devices had to have supports because of their weight and to align them with their shafts and because of vibration of the operating mechanism. In fact, the usual arrangement as for D_1 and its operating mechanism required too much time to study and lay out, had too many parts that were difficult to place and support and that were not pleasing to the eye when so installed and that required a specially trained man to plan for and erect same.

By this invention I overcome these difficulties as follows: In multiple effect compressor device D I omit the cam and its roller and shaft and guides and supply a piston for valve 2 and actuate valve 2 by means of its piston (hereafter called piston actuated valve) by means of a pipe leading from pressure imposing means actuated from the compressor's motive means as for example from its crank shaft. Such a pressure pipe is readily installed and can go around all kinds of parts that were so difficult to dodge with the shafts and gears, etc., of D_1 . This requires no special time to plan for its layout and is quickly and easily installed by an unskilled man and the pressure actuating means 16 is easily installed in like manner. The forms that multiple effect compressor device D or pressure actuating means 16 may have are many under the principle of this invention as will be clear to those skilled in the art without further detailed description. I may use the puppet type of valve as shown in D , or a type of valve as shown in Fig. 4, or in fact any known type of valve without departing from the method of this invention.

In Fig. 4, 5 is a low suction and 6 a high suction inlet and 7 the outlet to compressor and where piston 1—2 acts both as a suction and a discharge valve according to its posi-

tion as shown by the full or dotted lines. 1—2 may be pushed in one direction by piston 8 from pressure via pipe 17 and may be returned by any desired means *s*. It is evident that the simple multiple effect compressor device D of Fig. 1 can replace the complicated multiple effect compressor device D_1 .

Ordinary compressor A of Fig. 1 may be double acting, or by removing valves *i* and *j* on one side may be single acting and by the addition of one or more multiple effect compressor devices may be made multiple effect.

In Fig. 1 the discharge gas from *k* goes to condenser C and is liquefied and flows past expansion valve α to low pressure refrigerator E and is vaporized and flows to low suction inlet 5 and the liquid also flows past expansion valve γ and is vaporized in high pressure refrigerator F and flows to high suction inlet 6 of D .

A booster is an ordinary compressor that compresses from a low pressure to a higher pressure and discharges into the suction of an ordinary compressor. So a booster system is in effect a compound compression system.

Now in Fig. 1 if A_1 represents such a booster and if A were an ordinary compressor, then it is evident that the whole capacity of A would be used to take care of the discharge from the booster A_1 . But if A is a multiple effect compressor, then if F is a low pressure refrigerator and E is a high pressure refrigerator, then, the low pressure vapor from F is compressed by booster A_1 to a pressure superior to that of the vapor from E and so we have A , as a multiple effect compressor, having full capacity for vapor from E , and in addition, taking care of all of the compressed vapor from F via booster A_1 . This, by this invention, is quite an important improvement both as to capacity and economy, of a booster system.

Any desired pressure imposing fluid may be used to act on piston 8, such for example as air or any gas or vapor or such as water, brine, oil or any liquid.

The pressure of this fluid to move piston 8 may be imposed through the compressor's motive means or by any other means, timed to the compressor's piston's motion.

If a fluid that would contaminate the refrigerant is used, then, a separate cylinder and stuffing box are required for piston 8 as, for example, $8a$ in Figs. 2 and 3. Means, as vents 32 may be used, if piston $8a$ is used, to vent the back side of piston $8a$. These vents 32 may vent to any desired source of pressure and may help to assist or replace means *s*. I prefer to use a fluid which is either the refrigerant's gas or else is oil as used in lubrication of the compressor's piston, so as to avoid extra cylinders $8a$ and their stuffing boxes and still not contaminate the

refrigerant by leakage past piston 8 into the system.

In Fig. 2, 27 is a tank having any desired liquid 31 and vent 28. Pipe 25 leads from the lower end of tank 27 via check valve 23 to pressure imposing means 16, and liquid 31 follows piston 22, actuated in any desired manner. Then the motion of piston 22 is reversed and the liquid is pushed by piston 22 via pipe 17 to cylinders 18 and so pushes pistons 8 and 8a and so lifts valves 2 from their seats. Excess of liquid (there should be some excess) is vented via pipe 17 and pressure regulating valve 24, having adjusting means 24a, and pipe 26, back to tank 27. Liquid 31 may be cooled or heated by means of a cooling or heating fluid circulated through coil 29, 30, to warm the liquid if it is over-cooled in its operation of pistons 8 and 8a, or to cool the liquid if it is over-heated by friction or other causes. Liquid 31 may be water or brine, in which case piston 8a is used and 28 may vent to the air. Liquid 31 may be lubricating oil, in which case piston 8 is used and 28 may vent into a refrigerant vapor pipe.

In Fig. 3, any gas or vapor may be used; if the refrigerant's gas is used then piston 8 is used and if other gas is used then piston 8a is used. This fluid may be air or steam or any other gas. 5a is a low pressure and 6a a high pressure opening in 16 and 5a or 6a may open to opening 16b and so act via pipe 17 to cylinder 18 on piston 8 or 8a.

If refrigerant gas is used inlet 5a may connect to the high suction pipe or to the discharge pipe direct or via a pressure reducing valve (not shown) and outlet 6a may connect to the low suction pipe or to the high suction pipe.

In Figs. 6 and 7, shaft 9 rotates cam 3, of any desired shape to suit requirements, and so reciprocates roller 4 back and forth on line a, b, roller 4 being held in contact with cam by any desired means s. Such a cam and roller are used in D₁ and 16 of Fig. 1 and in 16 of Figs. 9 and 10.

In Fig. 8 the multiple effect compressor device D has low suction inlet 5 and high suction inlet 6 and outlet to compressor 7, the low suction valve 1 has cage and seat 20, cover 35 and spring s and the high pressure valve 2 has cage and seat 21, cover 36 with opening 18, spring s or vents 32, or both, and piston 8.

Low suction vapor enters 5 into chamber a and passes valve 1 and chamber c and outlet 7 to compressor. High suction vapor enters 6 to chamber c and passes out 7 to compressor.

Valve 2 is opened by piston 8 having packing rings 33 by fluid pressure via opening 18.

Two multiple effect compressor devices like that of Fig. 8 are shown at DD in Fig. 11 at each end of a double acting compressor

and at DD in Figs. 12 and 12a on each cylinder of the two cylinder single acting compressor.

In Fig. 1 two couplings 11 are shown. These couplings may be of any desired shape or type as in halves, bolted together. Either of these couplings if unbolted, stops rotation of shaft 9, beyond that point and allows for the relative adjustment of position of piston h and the cam 3 in D₁ or 16, so as to cause valve 2 to open at any desired position of piston h.

In Fig. 9, 40 is a key for one half of a coupling 11 of Fig. 1, shaft 9 has key 39 for cam 3, cam 3 is in contact with roller 4 on pin 34 in piston 22 having packing rings 33 and opposed as by spring s in cap 37 having opening 16a, cam 3 may have one or more other rollers like 4 to actuate one or more pistons 22, like 22. If pistons 22 and 22₁ are used, each serves to actuate a high pressure valve in each device as in D, D of Figs. 11 or 12 and 12a.

In Fig. 10, cam 3 and roller 4 actuate piston valve 22a, which because of its part 1—2 opposed as by spring s, can alternately open communication between ports 16b and 6a or between 16b and 5a to allow high or low pressure fluid to flow to or from opening 18 of Fig. 8 to actuate piston 8 of high pressure valve 2.

In Figs. 13 and 14 a four pressure multiple effect compressor device and its pressure imposing means 16 are shown. Here, for example, 0, 5, 10 and 15 pound pressures may be handled as shown, the 0 pressure (gage pressure) entering at 5 and then 5, 10, 15 pressures entering at 6, 6x and 6y, respectively, a cam in 16 varying pressure to pipes 17 and so actuating the piston actuated suction valves for 5, 10 and 15 pound pressure in the order named, the non-piston actuated valves for 0, 5, and 10 pound pressures, preventing back flow of the 5, 10 or 15 pound pressure to a lower pressure, as will be clear to those skilled in the art without further detailed description.

In Fig. 15, compressor A is of any desired type and is here shown as a conventional enclosed type of single acting compressor. Shaft 15 is revolved in any desired manner as by pulley 14a, from any desired source of power as by a belt (not shown) on 14a. Shaft 15 has conventional reciprocating means (not shown) for reciprocating a conventional piston (not shown) in cylinder Aa, provided with conventional suction and discharge valves (not shown), all of which will be clear to those skilled in the art, without further detailed description. F₁ and F₂ are refrigerators having expansion valves y_a and y_b. All other parts are as shown in former figures or combinations thereof. For example, 16 is as shown in Fig. 9 or Fig. 10 or a combination thereof. D may act as a two, three or

four pressure multiple effect compressor device. The casing of D Figs. 13, 14, may be used omitting or not operating one or two of the piston actuated valves therefor or therein.

5 Valved conduits 28a and 28b connect with refrigerators E and F and with conduit 28 and may cause pressure of E or F to be in 27 and valved conduit 28c connects 28 with the atmosphere so atmospheric pressure may be in 27. Any one of conduits 17 may actuate 10 any one of piston actuated valves in D, either by gas or hydraulic pressure action. Valved conduits to 5a and 6a are so that these conduits may or may not be used as may be desired, for any one or more of conduits 17, via 16.

In operation, any compressed refrigerant gas, for example, as ammonia, is discharged via *k* to condenser C and is therein liquefied 20 by the removal of heat therefrom and then flows to expansion valves *x*, *y*, *y_a*, *y_b* and therethrough and through refrigerators E, F, F₁, F₂, wherein it is vaporized by the addition of heat thereto.

25 Ordinary compressor A₁, may, or may not, be used, as is desired and when not in use it becomes a part of the conduit from F to D. Let A₁, be not in use, then any desired pressures may be used in the refrigerators by 30 the regulation of the expansion valves and by the quantities of heat given to the refrigerators. For example these gauge pressures may be 0 lbs. in E, 5 lbs. in F, 10 lbs. in F₁ and 15 lbs. in F₂. If expansion valves *y_a* and 35 *y_b* are closed then refrigerators F₁ and F₂ are out of action. Refrigerators E and F may operate at any desired pressures and with A₁ in action then E may operate at say 15 lbs. and F at say 0 lbs. and A₁ may compress vapor 40 from F from 0 lbs. to any desired pressure greater than that in E, as say 20 lbs. Variations of a fluid pressure in conduits 17, via 16, actuate piston valves in D. If hydraulic pressure is used in conduits 17 then it is preferable to use a tank 27 and its pipes 25, 26 are also in use for each conduit 17 so used. If gas pressure is used in conduits 17 then 45 conduits 25, 26 are blanked off and not in use.

When a piston actuated valve in D is hydraulically operated in conjunction with tank 27, then provided no gas trap is caused thereby, conduits 25 and 17 may join and communicate with opening 16a, *b* as shown in Fig. 15, or each may enter the upper end of cylinder 22 as shown in Fig. 2.

As shown in Fig. 15, the left hand vertical conduit 17, from 16, is used hydraulically and the other two conduits 17 are used pneumatically or all three conduits 17 may be used hydraulically by adding two other tanks 27 for the two other conduits 17 or all three conduits 17 may operate pneumatically, as by gas, with tank 27 not in use, either by blanking off its pipes 25, 26, or by closing regulating valve 24 and causing valve 23 not to act.

Referring again to Fig. 2, it is seen that conduits 17, 25, 26 are either horizontal or vertical so as not to form any place wherein air or gas could accumulate to form gas traps. The piston actuated valve's cylinder and conduit 17 are so disposed that air or gas could not be trapped in said cylinder and 23 and 24 are so disposed as to be free from gas traps.

Such gas traps would, because of alternate compression and reexpansion of air or gas therein, cause the high pressure suction valve's piston to function improperly or not at all. Similarly in Fig. 15, such conduits are either vertical or horizontal or slope up from 16 to D and 27 and from D to 27. All so adapted that any air or gas in the pressure imposing pipes and their connections will work its way up into 27 and from there into the atmosphere or into a refrigerator. It is obvious that with A₁ in use that A₁ will have greater capacity and economy than if it discharged directly into the higher pressure of a condenser and if it discharges into a higher pressure than that of E, that I then have compressor cylinder A_a full at E pressure and then its full capacity, less the reduced volume at E pressure, for vapor from F, at such a pressure from A₁ as will adjust itself so that vapor from A₁ can get into the compressor via D after having compressed the vapor from E in the cylinder to its pressure, i. e. the pressure from A₁.

In the claims where I use the words "piston valve" I mean a high pressure suction valve adapted to be opened by a piston directly or indirectly connected thereto, by means of a fluid pressure exerted on said piston.

What I claim is:

1. A multiple effect compressor device for gas compressors comprising a main chamber and two pressure chambers, an opening in each chamber for connection of a suction conduit thereto, each of said pressure chambers having a port opening therefrom into the main chamber, a valve governing one port, a piston actuated valve governing the other port, a spring causing said piston actuated valve to cover its port, a cylinder for said piston actuated valve's piston and an opening in the cylinder for connection of a conduit thereto. 105 110 115

2. A multiple effect compressor device for gas compressors comprising a main chamber and two pressure chambers, an opening in each chamber for connection of a suction conduit thereto, each of said pressure chambers having a port opening therefrom into the main chamber, a valve governing one port, a piston actuated valve governing the other port, means to cause the piston actuated valve to cover its port, a cylinder for said piston, actuated valve's piston, an opening in the cylinder for connection of a conduit thereto, said piston actuated valve, its port and cylinder being so disposed that an increase of fluid pressure to the opening of 120 125 130 135 140 145 150 155 160 165 170 175 180

said cylinder will cause said piston actuated valve to uncover its port.

3. A multiple effect compressor device for gas compressors comprising a main chamber and a plurality of pressure chambers, each chamber having an opening therein for connection of a suction conduit thereto, each of the pressure chambers having a passage to the main chamber, the lowest pressure chamber having a nonreturn valve governing its passage, the other pressure chambers having piston actuated valves governing their inlets to their passages and nonreturn valves for all but the highest pressure passage's outlets, 10 springs causing said piston actuated valves to cover the inlets to their passages, a cylinder for each piston actuated valve's piston and an opening in each cylinder for connection of a conduit thereto.

20 4. A multiple effect compressor device for gas compressors comprising a main chamber and a plurality of pressure chambers, each chamber having an opening therein for connection of a suction conduit thereto, each of the pressure chambers having a passage to the main chamber, the lowest pressure chamber having a nonreturn valve governing its passage, the other pressure chambers having piston actuated valves governing their inlets 25 to their passages and nonreturn valves for all but the highest pressure passage's outlets, means causing said piston actuated valves to cover the inlets to their passages, a cylinder for each piston actuated valve's piston, an 30 opening in each cylinder for connection of a conduit thereto, said piston actuated valves and their passages and their cylinders, being so disposed that an increase of pressure to the openings of said cylinders will cause said piston actuated valves to uncover the inlets to 35 their passages.

5. A fluid pressure imposing means for a multiple effect compressor device's piston actuated valve's piston comprising a casing and an extension of a compressor's shaft, said shaft's extension having means causing a change of pressure of a fluid in said casing during a portion of the shaft's revolution.

6. A fluid pressure imposing means for a multiple effect compressor device, piston actuated valve's piston comprising a cam shaft forming an extension of a gas compressor's shaft, a casing, a stuffing box therein for the shaft, a cam on the cam shaft, a piston, a cam 55 roller for the piston, means to press the roller against the cam, a piston's cylinder having an opening therein for connection of a conduit thereto, all so combined that a revolution of the cam shaft will cause the cam to cause the roller to reciprocate the pistons to cause a change of pressure of a fluid in the cylinder for a portion of the revolution of the cam shaft.

7. A fluid pressure imposing means for a 65 multiple effect compressor device, piston ac-

tuated valve's pistons comprising a cam shaft forming an extension of a gas compressor's shaft, a casing, a stuffing box therein for the shaft, a cam on the cam shaft, a plurality of pistons, a plurality of rollers for the pistons, means to press the rollers against the cam, a plurality of piston's cylinders, each having an opening therein for connection of a conduit thereto, all so combined that a revolution of the cam shaft will cause the cam to cause the rollers to reciprocate the pistons to cause a change of pressure of a fluid in each cylinder for a portion of the revolution of the cam shaft.

8. In a gas compressing system, the combination of a compressor's cylinder and a piston therein, a suction and a discharge valve therefor, a shaft to actuate the piston, a multiple effect compressor device having a low pressure suction valve and a high pressure suction piston actuated valve, a passage from these valves to the compressor's suction valve, and a fluid pressure imposing means comprising an extension of the shaft of the compressor connected to a movable means causing a fluid's pressure to change during a portion of the shaft's revolution, a conduit from the fluid pressure imposing means to the piston actuated valve.

9. A multiple effect compressor device for gas compressors comprising a main chamber and two pressure chambers, an opening in each chamber for connection of a conduit thereto, each of said pressure chambers having a port opening therefrom into the main chamber, a valve governing one port, a piston actuated valve governing the other port, means, other than a fluid pressure on said piston, causing said piston actuated valve to cover its port, a cylinder for said piston actuated valve's piston having an opening in the cylinder for connection of a conduit thereto.

10. A multiple effect compressor device for gas compressors comprising a main chamber and two pressure chambers, an opening in each chamber for connection of a conduit thereto, each of said pressure chambers having a port opening therefrom into the main chamber, a valve governing one port, a piston actuated valve governing the other port, a cylinder for said piston actuated valve's piston having an opening in the cylinder for connection of a liquid conduit thereto.

11. A multiple effect compressor device for gas compressors comprising a main chamber and two pressure chambers, an opening in each chamber for connection of a conduit thereto, each of said pressure chambers having a port opening therefrom into the main chamber, a valve governing one port, a piston actuated valve governing the other port, a means, other than a fluid pressure on said piston, causing said piston actuated valve to cover its port, the piston actuated valve having a stem extending through the main

chamber, joining its piston and its valve, a cylinder for said piston having an opening in the cylinder for connection of a conduit thereto.

- 5 12. A multiple effect compressor device for gas compressors comprising a main chamber and two pressure chambers, an opening in each chamber for connection of a conduit thereto, each of said pressure chambers having a port opening therefrom into the main chamber, a valve governing one port, a piston actuated valve governing the other port, said piston actuated valve having a stem extending from its valve to its piston, a stuffing 70 box for said stem, a cylinder for said piston actuated valve's piston having an opening in the cylinder for connection of a conduit thereto.
- 10 13. In a multiple suction system comprising a multiple effect compressor device, a pressure imposing means and a liquid tank, a liquid conduit from the pressure imposing means to a multiple effect compressor device and from the multiple effect compressor device to the liquid tank and from the liquid tank to the pressure imposing means.
- 15 14. In a multiple suction system, the combination of a liquid conduit extending from a pressure imposing means to a piston actuated valve's piston, and means venting gas and some liquid from said conduit during its pressure imposing period or during movement of the piston by the liquid or during its cycle of operations.

- 30 15. In a valve actuating system, the combination of a piston actuated valve, means to cause said valve to close, a pressure imposing piston, cylinders for said pistons, a conduit extending from the pressure imposing cylinder to the valve cylinder, a conduit extending from the highest portion of said conduit or cylinders to the pressure imposing cylinder, a regulating valve venting said highest portion to a return conduit, a return 90 conduit leading from said regulating valve to the pressure imposing cylinder, a check valve in said conduit, said conduits, valves and cylinders being so disposed that gas or vapor that might otherwise tend to accumulate 95 in any portion thereof will accumulate and vent itself either through the regulating valve or check valve or both into the return conduit.
- 35 16. In a valve actuating system, the combination of a piston actuated valve, means to cause said valve to close, a pressure imposing piston, cylinders for said pistons, a conduit extending from the pressure imposing cylinder to the valve cylinder, a conduit extending from the highest portion of said conduit or cylinders to the pressure imposing cylinder, a regulating valve venting said highest portion to a return conduit, a return 100 conduit leading from said regulating valve to the pressure imposing cylinder, a check valve in said conduit, said conduits, valve, and cylinders being so disposed that gas or vapor that might otherwise tend to accumulate in any portion thereof will accumulate and vent itself either through the regulating valve or check valve, or both, into the return conduit, a vent from 105 said return conduit.

- 40 17. In a valve actuating system, the combination of a piston actuated valve, means to cause said valve to close, a pressure imposing piston, cylinders for said pistons, a conduit extending from the pressure imposing cylinder to the valve cylinder, a conduit extending from the highest portion of said conduit or cylinders to the pressure imposing cylinder, a regulating valve venting said highest portion to a return conduit, a return 110 conduit leading from said regulating valve to the pressure imposing cylinder, a check valve in said conduit, said conduits, valves, and cylinders being so disposed that gas or vapor that might otherwise tend to accumulate in any portion thereof will accumulate and vent 115
- 45 18. In a valve actuating system, the combination of a piston actuated valve, means to cause said valve to close, a pressure imposing piston, cylinders for said pistons, a conduit extending from the pressure imposing cylinder to the valve cylinder, a conduit extending from the highest portion of said conduit or cylinders to the pressure imposing cylinder, a regulating valve venting said highest portion to a return conduit leading from said regulating valve to the pressure imposing cylinder, a check valve in said conduit, said conduits, valve, and cylinders being so disposed that gas or vapor that might otherwise tend to accumulate in any portion thereof will accumulate and vent itself either through the regulating valve or check valve, or both, into the return conduit, a vent from 120 said return conduit.
- 50 19. In a valve actuating system, the combination of a piston actuated valve, means to cause said valve to close, a pressure imposing piston, cylinders for said pistons, a conduit extending from the pressure imposing cylinder to the valve cylinder, a conduit extending from the highest portion of said conduit or cylinders to the pressure imposing cylinder, a regulating valve venting said highest portion to a return conduit, a return conduit leading from said regulating valve to the pressure imposing cylinder, a check valve in said conduit, said conduits, valves, and cylinders being so disposed that gas or vapor that might otherwise tend to accumulate in any portion thereof will accumulate and vent 125
- 55 60 65

valve in said conduit, said conduits, valves and cylinders being so disposed that gas or vapor that might otherwise tend to accumulate in any portion thereof will accumulate and vent itself either through the regulating valve, or check valve, or both, into the return conduit, a liquid receiver in said return conduit between said valves.

70 17. In a valve actuating system, the combination of a piston actuated valve, means to cause said valve to close, a pressure imposing piston, cylinders for said pistons, a conduit extending from the pressure imposing cylinder to the valve cylinder, a conduit extending from the highest portion of said conduit or cylinders to the pressure imposing cylinder a regulating valve venting said highest portion to a return conduit, a return 80 conduit leading from said regulating valve to the pressure imposing cylinder, a check valve in said conduit, said conduits, valves, and cylinders being so disposed that gas or vapor that might otherwise tend to accumulate in any portion thereof will accumulate and vent itself either through the regulating valve or check valve, or both, into the return conduit, a liquid receiver a portion of which is located higher than the vent to the regulating valve in said return conduit between 85 said valves.

90 18. In a valve actuating system, the combination of a piston actuated valve, means to cause said valve to close, a pressure imposing piston, cylinders for said pistons, a conduit extending from the pressure imposing cylinder to the valve cylinder, a conduit extending from the highest portion of said conduit or cylinders to the pressure imposing cylinder, a regulating valve venting said highest portion to a return conduit leading from said regulating valve to the pressure imposing cylinder, a check valve in said conduit, said conduits, valve, and cylinders being so disposed that gas or vapor that might otherwise tend to accumulate in any portion thereof will accumulate and vent itself either through the regulating valve or check valve, or both, into the return conduit, a vent from 95 said return conduit.

100 19. In a valve actuating system, the combination of a piston actuated valve, means to cause said valve to close, a pressure imposing piston, cylinders for said pistons, a conduit extending from the pressure imposing cylinder to the valve cylinder, a conduit extending from the highest portion of said conduit or cylinders to the pressure imposing cylinder, a regulating valve venting said highest portion to a return conduit, a return conduit leading from said regulating valve to the pressure imposing cylinder, a check valve in said conduit, said conduits, valves, and cylinders being so disposed that gas or vapor that might otherwise tend to accumulate in any portion thereof will accumulate and vent 105

- itself either through the regulating valve or check valve or both into the return conduit, a liquid receiver a portion of which is located higher than the vent to the regulating valve
- 5 in said return conduit between said valves, a vent from said return conduit.
20. In a multiple effect compressor device, the combination of a longitudinal chamber having a closed and an open end, the open end
- 10 being adapted for connection to a suction conduit leading to a compressor, three side openings in the chamber, each being adapted for connection of a conduit thereto, two of the
- 15 side openings being near the chamber's open end, a low pressure puppet suction valve in the chamber near its closed end, a piston actuated high pressure suction valve in the chamber near its open end, the side opening near the chamber's closed end communicat-
- 20 ing with the puppet suction valve's inlet side, one of the other side openings communicating with the high pressure suction valve's piston and the other communicating with the inlet side of its valve, the chamber, valves, and
- 25 openings being so disposed as to form a main chamber communicating with the longitudinal chamber's open end and two chambers each communicating with the main chamber via a suction valve.
- 30 21. In a multiple effect compressor device, the combination of a longitudinal chamber having a closed and an open end, the open end
- 35 being adapted for connection to a suction conduit leading to a compressor, three side openings in the chamber, each being adapted for connection of a conduit thereto, two of the
- 40 side openings being near the chamber's open end, a low pressure puppet suction valve in the chamber near its closed end, a piston actuated high pressure suction valve in the chamber near its open end, the side opening near the chamber's closed end communicating
- 45 with the puppet suction valve's inlet side, one of the other side openings communicating with the high pressure suction valve's piston and the other communicating with the inlet side of its valve, the chamber, valves, and
- 50 openings being so disposed as to form a main chamber communicating with the longitudinal chamber's open end, and two chambers each communicating with the main chamber via a suction valve, two of the side openings being in line and one of these openings being
- 55 opposite the other opening, near the longitudinal chamber's open end.
